UNITED STATES PATENT OFFICE

ALBERT W. ENGEL, OF CHICAGO, ILLINOIS

ENVELOPE

Application filed August 10, 1925. Serial No. 49,271.

The purpose of this invention is to provide an envelope fitted with pockets in one or more of its walls and adapted for construction by simple and economical methods. It consists of certain features and elements of construction herein shown and described as indicated by the claims.

In the drawings:—

Figure 1 is a plan view of an envelope embodying this invention showing the same in open position.

Figure 2 is a plan view of said envelope showing the flap partially unfolded to disclose its construction.

Figure 3 is a modification showing the use of an envelope flap embodying this invention applied to an otherwise standard form of envelope.

As shown in Figure 1 the envelope comprises a front wall, 1, having a closure flap, 2, extending from its upper edge, said flap being formed with a pocket whose open edge, 3, is disposed adjacent the crease, 4, at which the flap is folded over in closing the envelope. The flap is conveniently formed by cutting the blank for it as shown in Figure 2 with a substantially square outline, forming diagonal creases in the square and then removing the triangle remote from and directly opposite the crease, 4. This leaves two triangles, 5 and 6, which may be folded down over a third triangle, 7, with the part, 6, on top; a marginal flap, 8, on the triangle, 6, may then be tucked into the pocket thus formed overlapping the triangle, 5, and firmly locking the parts in folded position. A flap of this nature forms a convenient pocket for enclosing small sample articles such as postage stamps, gummed tabs, labels or other stickers or small samples of cloth and the like. It will be evident that this type of flap may be applied to a standard envelope such as that shown at 20 in Figure 3.

In the preferred form of my invention shown in Figures 1 and 2, the envelope includes a back wall, 10, having a slit at 11 to receive the pointed tip of the closure flap, 2, and additional flaps, 12, are formed of material continuous with the walls, 1 and 10, at their ends and folded over upon said walls.

Preferably these end flaps, 12, include triangular terminal portions, 13, which extend into the pocket of the flap, 2, thus serving to lock the flaps, 12, in their folded position in which they form four pockets, two on the front wall and two on the back wall of the envelope, in pairs opening toward each other and toward the middle of the width of the envelope.

At the opposite end of the blank a terminal flap, 14, is turned up from the edge of the back wall, 10; this flap is cut apart at the line, 15, so that triangular tabs, 16, may be formed by folding back the cut corners along the oblique lines, 17. By tucking these corners under the flap, 12, as indicated in Figure 1 and serving to lock down the flaps, 12, at this end of the blank. If desired the parts may be still more securely held in place by the engagement of locking tabs, 18, on the flap, 14, in slots, 19, formed in the two pocket flaps, 12.

It will be seen that an envelope constructed according to this invention may serve a wide variety of uses and is particularly adapted to be employed as a merchandise carrier although if desired it may also be used to enclose first class mail matter.

I claim—

1. In an envelope, a body and a closure flap extending from a creased base line at one side of the body, said flap being formed from a substantially square blank creased at its diagonals and thus sub-divided into four triangles, the middle triangle remote from the base line being cut away and the lateral triangles being folded over each other and over the remaining middle triangle to form therewith a pocket opening toward the base line; one of said lateral triangles having a locking flap extending substantially throughout the length of the open side of said pocket and adapted to be tucked into the pocket over the edge of the other lateral triangle to hold them together.

2. An envelope formed from a blank of sheet material folded upon itself to provide a front wall and a back wall, said sheet including end flaps each extending continuously from the adjoining ends of said walls, said adjoining ends being defined by creases along

which the end flaps are folded over the inner faces of said front and back walls partially overlapping them and thus forming pockets opening inwardly from the ends of the envelope and toward the middle of its length; and a closure flap on one of said walls adapted to overlap and engage the other wall, said closure flap being itself a pocket joined to one wall at a line of fold and opening toward said line, and said end flaps having terminal portions which extend into the pocket of the closure flap for locking said end flaps in position.

In testimony whereof, I have hereunto set my hand at Chicago, Illinois, this 21st day of November, 1923.

ALBERT W. ENGEL.
